UNITED STATES PATENT OFFICE.

JOSEPH CHARLES GUSTAVESON, OF PROVIDENCE, UTAH.

NON-REFILLABLE BOTTLE.

SPECIFICATION forming part of Letters Patent No. 728,099, dated May 12, 1903.

Application filed June 16, 1902. Serial No. 111,890. (No model.)

To all whom it may concern:

Be it known that I, JOSEPH CHARLES GUSTAVESON, a citizen of the United States, and a resident of Providence, in the county of Cache and State of Utah, have made certain new and useful Improvements in Non-Refillable Bottles, of which the following is a specification.

My invention is an improvement in non-refillable bottles, having for an object to provide a novel construction which will permit the contents of the bottle to be dispensed, but will prevent the refilling of the bottle and will include means whereby to prevent the insertion of wires or other instruments to displace the valves arranged to prevent refilling of the bottle; and the invention consists in certain novel constructions and combinations of parts, as will be hereinafter described and claimed.

In the drawings, Figure 1 is a perspective view of the upper portion of a bottle provided with my improvements. Fig. 2 is a vertical longitudinal section thereof. Fig. 3 is a cross section on about line 3 3 of Fig. 2. Fig. 4 is a detail perspective view of the guard-plug and its retaining-lugs, and Fig. 5 is a detail perspective view of the valve for preventing the refilling of the bottle. Fig. 6 is a sectional view showing a somewhat different construction from that shown in Fig. 2, and Fig. 7 is a longitudinal section of part of the bottle placed on the side, with arrows indicating the course of the liquid in dispensing the same.

The bottle A may in general respects be of ordinary construction or form. In carrying out my invention I provide a contracted opening at A', through which the bottle may be filled and emptied, such opening leading to the valve-chamber B, above which I provide an internal annular groove C in the neck of the bottle to receive the guard presently described. The bottle-neck may be prolonged at C' above the groove C, and where desired a cork may be put in the upper end of the neck, as shown at D in Fig. 6.

The valve-chamber B is provided with a circumferential outwardly-swelled portion B', which communicates at its upper end by the channel B² with the neck of the bottle, the channel B² opening immediately below the

guard presently described. I also provide the chamber B with a number of longitudinal channels B³, which may merge at their middles in the recess B' and form at their ends passages communicating with the chamber B² and also with the opening A' when the valve E (shown in Fig. 5) is unseated.

The valve E may be of cork or other suitable material and is of a special form, being tapered at E' at its lower end to form a closure for the opening A', as shown in Fig. 2, and being grooved at E² in its upper end to form a seat to one side of its center E³ for the glass ball F (see Fig. 2) in the position of the parts shown in said Fig. 2.

The guard is in the form of a plug G, having circuitous passages G' in its sides and provided with the laterally-extending spring-pressed lugs or keys H, which are pressed outwardly into the groove C by the cork or other spring H', as shown in Fig. 2. It will be noticed from Figs. 2 and 4 that the plug has a transverse opening formed through it in which the lugs H and the spring H' for actuating the same operate.

The guard serves a double purpose in that it operates to retain the valve E and the ball F and also prevents the insertion of a wire or other instrument for the purpose of displacing the said ball or valve in order to refill the bottle.

In Fig. 6 the valve E shown in Figs. 2 and 5 is replaced by a ball-valve I, the construction being otherwise similar to that shown in the other figures and the same form of guard being employed.

The valve E is held in line with its seat and from falling to either side by fitting it in the guideway e, provided by the inner edges of the walls of the channels B³, below the circumferential recess for the valve-controlling ball F, so the valve E is held at all times in line with its seat A', and yet can move longitudinally toward and from the said seat. When the bottle is in the position shown in Fig. 2, the glass ball resting on the valve holds the valve down to its seat, and if the bottle be placed on one side the ball F will still rest on the edge of the valve and will hold the same to its seat, so the bottle cannot be filled when supported in the horizontal position. If the bottle be turned nearly upside down,

the ball F will fall down into the channel B², as indicated in dotted lines, Fig. 2, and the valve E will fall onto the ball, thus leaving room for the liquid to pass out through the channels B³, and thence through the circuitous passages G' in the guard G to discharge at the mouth of the bottle. If while the bottle is in this inverted position an effort is made to fill the bottle by means of a hose attached to its mouth, the valve E, which is made of cork or some other light substance, will float up to and close the opening A'.

It may be preferred to call the recess B' in which the ball F lies when the bottle is on its side the "dump," because when the bottle is turned from the upside-down position, so that it rests on the side, the ball will dump off the edge b² and push the valve E to closed position. It will be noticed the distance between the edge b² and the inner end of the guard G is less than one-half the diameter of the ball F, so the ball will dump off the edge b² before the bottle is adjusted to horizontal position.

25 In operation the cork or other material spring H' may be steamed or compressed before inserting it in the guard-plug and the bars H, of glass, wood, or other material, be inserted in the opposite ends of the transverse opening in the plug and pressed inwardly, so they will be flush with the surface of the plug, so the latter can be pressed into the neck of the bottle until the locking-lugs are opposite the groove C, when the spring 35 will force the said lugs out into the groove and lock the guard in place.

In the use of the bottle after the same has been filled the cork valve is first inserted, followed by the ball F, and then the guard is 40 inserted, as before described.

Having thus described my invention, what I claim as new, and desire to secure by Letters Patent, is—

1. The improvement in non-refillable bottles herein described consisting of the bottle proper provided with a valve-chamber and with a neck portion extending therefrom and having an integral groove, an opening being provided between the body of the bottle and 45 the valve-chamber, and the latter being provided with guides leading from said opening for the valve and with a circumferential re-

cess and with longitudinal channels on opposite sides of said recess and having the walls of said channels at the upper end of 55 the valve-chamber arranged to form bearings for the valve-controlling ball, the valve sliding in the guides of the valve-chamber toward and from its seat and having in its outer end a groove or recess for the controlling-ball, the controlling-ball operating in said recess and against the valve, and the guard in the bottle-neck substantially as set forth.

2. The combination of the bottle having a valve-chamber, the valve arranged at its inner end to control the discharge from the bottle and having in its outer end a groove surrounding its center, and the ball operating in the grooved outer end of the valve in one position of the parts and opposite the central 70 elevation in another position of the parts, substantially as set forth.

3. The combination with the bottle having a valve-chamber and a valve-seat, the valve fitted to said seat and having an annular 75 groove in its outer end and a central elevation within the groove, and the ball operating in said groove in one position of the parts and against the central elevation in another position of the parts, substantially as set 80 forth.

4. A bottle having a valve-chamber provided with longitudinal channels for the liquid, the walls of said channels being arranged at their inner ends to form guides for the valve and at their outer ends to provide a recess for the valve-controlling ball, and the valve and ball substantially as set forth.

5. A bottle having a valve-chamber provided with a central annular recess and above 90 and below the same with longitudinal channels leading to the said recess substantially as set forth.

6. A bottle having its neck provided with a valve-chamber having longitudinal channels at its ends and an intermediate recess and provided between said valve-chamber and the mouth of the bottle with guard devices substantially as set forth.

JOSEPH CHARLES GUSTAVESON.
